United States Patent Office

Des. 221,741
Patented Sept. 7, 1971

221,741

FOOD SERVICE BUILDING

James T. Hight, Fairfield, Conn., assignor to
American Dairy Queen Corporation

Filed Mar. 17, 1970, Ser. No. 21,936

Term of patent 14 years

Int. Cl. D25—03

U.S. Cl. D13—1

FIG. 1.

FIG. 2.

Des. 221,741

PAGE 2

FIG. 1 is a perspective view of my food service building, and

FIG. 2 is a top plan view thereof; and

FIG. 3 is a front elevational view thereof; and

FIG. 4 is a back elevational view thereof; and

FIG. 5 is an elevational view of one side thereof; and

FIG. 6 is an elevational view of the other side.

I claim:

The ornamental design for a food service building, as shown.
